TEXAS.

MINING OF SULPHUR.

Original application filed March 15, 1924, Serial No. 699,448. Divided and this application filed March 18, 1926. Serial No. 95,542.

This invention relates to improvements in the mining of sulphur, and includes an improved method for the mining of sulphur by underground fusion, as well as an improved system or apparatus therefor.

In the mining of sulphur by underground fusion, in accordance with the so-called Frasch process, a hole or well is drilled through the overlying strata to the bottom 10 of the sulphur formation, which hole is usually cased with an eight-inch or ten-inch pipe, and then, through a system of concentric pipes appropriately arranged within this casing, superheated water is 15 pumped down to the foot of the hole or well where it is discharged into the sulphur formation and melts the sulphur. The melted and liquid sulphur enters one of the concentric pipes, usually through a strainer, and 20 is raised to the surface of the ground, generally by means of an air lift. The well continues to operate and produce sulphur until the sulphur-bearing formation is locally exhausted, or until the piping equipment is broken by subsidence of the ground 25 due to the extraction of the sulphur content.

The sulphur formation is usually found in the form of so-called domes, at depths 30 varying from around 500 to 1500 feet below the surface of the ground. These sulphur domes are usually overlaid by a porous cap rock formation of limestone which in turn is overlaid by gumbo, quicksand and 35 clay. Beneath the sulphur formation is usually found a layer of gypsum or anhydrite, and layers or domes of salt.

The sulphur formation itself usually contains the sulphur distributed in a porous 40 rock formation which also contains a large amount of water forming what may be considered an underground lake of brine or salt water containing, for example, about 4800 grains per gallon of solids in solution, 45 mainly sodium chloride, and in addition hydrogen sulphide and other soluble sulphides.

In the so-called Frasch system of mining sulphur by underground fusion, hot water 50 is the vehicle commonly used for conveying and transmitting heat to the sulphur. Inasmuch as sulphur melts at a temperature

around 240° F., which is above the boiling point of water at atmospheric pressure, the heating water is highly superheated and is 55 pumped into the mine under a high pressure. The temperature to which the water can be superheated is however limited by the danger of overheating the sulphur in which case it becomes viscous. Accordingly, the 60 water is heated to a temperature which avoids overheating of the sulphur but which is sufficiently above the melting point of the sulphur to bring about effective melting thereof as the highly heated water 65 comes in contact with the underground sulphur. The water may thus be heated under pressure to about 320° F. and pumped into the sulphur deposit, this water replacing the sulphur removed by the well together with water already contained in the deposit, which may be withdrawn by means of bleed-wells, situated at suitable points in the deposit. The bleed-wells are usually located so as to withdraw the cold brine or 70 salt water from the lower part of the sulphur formation.

The sulphur dome may underlie a considerable surface area of ground. The dome may, for example, be as much as a mile in 80 diameter; and the underground lake forming a part of the deposit or adjacent thereto may contain billions of gallons of underground water or brine.

In the mining of such a sulphur deposit, one or several wells are usually drilled and operated at one part of the deposit until the sulphur bearing formation is exhausted locally and then other wells are drilled at another part of the deposit, and the deposit is progressively worked in this way until exhausted. The operation of a sulphur mine in this way is an operation of large 90 magnitude. The amount of highly heated water which it is necessary to pump into the deposit in a single day may amount to several million gallons in commercial operations.

The pumping of a large amount of superheated water into the deposit results in the 100 gradual accumulation of a progressively increased amount of hot water in the deposit. The specific gravity of the original deposit water is for example about 1.08, and the

temperature for example about 108° F.; while the specific gravity of the clean hot water pumped into the mine is in the neighborhood of 0.91. Owing to this difference in specific gravity, the hot water rises or tends to rise to the top of the dome, displacing the cold deposit water downward, and, while there is some diffusion and mixing, in a general way the water at the top 10 of the dome becomes cleaner and hotter with only a small amount of solids in solution, while the water in the lower part of the deposit contains its original content of dissolved solids until displaced by the 15 cleaner water from above.

The continued supply of a large amount of highly heated water to the mine forms one of the major expenses of the operation, this water being commonly obtained from a 20 source several miles distant from the mine at a temperature around, for example, 68° F., and being heated to a temperature around 324° F. before it is pumped into the mine. Of the total heat supplied to the 25 water, only a small part is available for melting the sulphur. Thus, in heating water from 68° F. to 324° F., 256 B. t. u.'s are supplied by the combustion of fuel to each pound of water which is pumped into the deposit. Since sulphur melts at around 30 240° F., the only effective heat supplied to the water is that between the maximum temperature of the water and the melting point of sulphur, for example, around 85 B. t. u.'s of the total of 256 B. t. u.'s supplied to the water.

The present invention provides an improved method and system of mining sulphur whereby important economy of operation 40 is obtained, and whereby a greatly increased fuel efficiency, and decreased fuel consumption can be effected. The present application is a continuation of my prior application, Serial No. 699,448, filed March 15, 45 1924.

The present invention is of particular advantage in the mining of sulphur from deposits which have been operated for considerable time until there has accumulated 50 a large amount of hot water in the upper portion of the dome or formation from which the sulphur has been exhausted. After long periods of operation, the temperature of this hot water, accumulating in the upper portion 55 of the dome, will be considerably above the melting point of sulphur, which is about 240° F., and the temperature of this water may be as high as 300° F., or even higher. This hot water is contained under considerable pressure, which pressure is usually 60 in excess of the hydrostatic pressure.

According to the present invention, I make further use of the accumulated hot water in the dome and take advantage of 65 the heat which it contains so that it becomes

unnecessary to supply additional fresh hot water to the sulphur deposit for use in the further mining of sulphur, or so that only a minimum amount of additional heat need be supplied, and, where supplied, can be 70 supplied without supplying further amounts of fresh hot water.

In the carrying out of the present invention, I withdraw hot water from the top or upper part of the dome or deposit where 75 it accumulates in the exhausted area and in the porous caprock, and I maintain this water at a temperature above the boiling point of water at atmospheric pressure by keeping the water under pressure while 80 it is being withdrawn, and I again force it down into the deposit while maintaining it under pressure through the well where the active mining operation is going on.

Where the water withdrawn is sufficiently 85 hot, i. e., sufficiently above the melting point of sulphur, it can be maintained at its high temperature and reintroduced into the deposit through the active sulphur mining well with only a small loss in temperature. The 90 hot water so introduced in the localized well zone will tend to rise again, after serving its purpose of melting sulphur, to unite with the large body of hot water in the top of the deposit. The gradual withdrawal of 95 hot water in this way, with return of the hot water withdrawn to the deposit, will result in a tendency to reduce the temperature of the hot water in the deposit, but after a 100 deposit has been operated a long period of time, the underground lake of hot water will be so large that water can be withdrawn from it and pumped back into the operating well or wells for long periods of time without reducing the temperature of the hot 105 water below that at which it is effective for the mining operation.

The process of the present invention can be carried out to particular advantage when the original mine water has been substantially all withdrawn from the sulphur deposit through bleed-wells from the lower levels of the deposit and when this water has been replaced by hot water. By then withdrawing hot water at the same rate at 110 which it is introduced into the active wells, the amount of underground hot water remains substantially constant.

In the carrying out of the process of the 115 invention the hot underground water, which is at a high temperature and pressure, e. g. considerably in excess of 240° F., and up to around 300° F., or more, and at a pressure greater than atmospheric, is withdrawn and 120 kept under pressure while it is being withdrawn, by means of a pump, a steam injector or other suitable means, and this water so withdrawn under pressure and with a temperature maintained by the pressure and by 125 preventing vaporization, is again introduced 130

into the deposit for further use in the mining operation.

One advantageous method of maintaining this water under pressure, and of preventing it from being cooled below 240° F., through reduction of its pressure, is to introduce a centrifugal pump into the line through which the water is withdrawn, and at a sufficiently low level to receive the water 10 while still under sufficient pressure to prevent its partial vaporization.

The hot water thus withdrawn may, if desired, be purified, but ordinarily it can be used again without purification. So also, 15 the water withdrawn may be subjected to further heating, as by injection of steam, but if the water is at a sufficiently high temperature it can be used again without further heating.

20 The invention will be further described in connection with the accompanying drawing, which illustrates in a conventional and graphic manner a section of a mine and of apparatus embodying the invention and 25 adapted for the practise of the process of the invention.

The showing is largely conventional, and various parts are magnified, and the horizontal dimensions of the pipe and of various 30 parts are magnified for convenience of illustration.

In such a mine as represented in the accompanying drawing, the sulphur deposit is usually overlaid by a caprock formation 35 of limestone, above which is gumbo, quicksand and clay. Below the sulphur deposit there are usually bodies of gypsum and salt. In the drawing, there is represented a region marked "hot water zone" from which 40 it is assumed the sulphur has been melted, and which is assumed to be full of hot water accumulated from the mining operation. The hot water will also extend upwardly into the porous caprock. It will 45 be apparent that as the sulphur is melted and withdrawn, the space originally occupied by the sulphur must be filled either by the subsidence of the earth above or by the hot water pumped into the mine. It 50 will also be understood, as above explained, that the hot water which is pumped into the mine, where the active mining operation is going on, is lighter than the cold salt water originally contained in the mine, so that the 55 fresh hot water tends to rise and to accumulate in the upper levels of the dome.

In the drawing, one of a series of active sulphur wells is indicated at 1, this well being made up as usual of a series of concentric pipes within a casing tube. For 60 convenience of illustration, the entire series of pipes is omitted and only two concentric pipes are shown, the inner pipe 3 being intended to illustrate graphically the pipe 65 through which the molten sulphur is pumped

from the mine and which extends to the bottom of the deposit, and the outer casing 2 illustrating the outer pipe within which the hot water is pumped down into the mine.

A bleed-well 5 is shown as located at a 70 distance from the active sulphur mine and as leading from a lower level of the deposit from which the colder water may be withdrawn in regulated amount.

A well 6 is shown as located so as to 75 withdraw water from the top of the dome.

This well extends down into the porous caprock and at its upper end is enlarged so as to accommodate a suitable pump, shown as a centrifugal pump 8 driven by a motor 9 and having an extension 10 extending down into the hot water zone and which may terminate in a perforated end 11 through which the hot water is admitted into the pipe 10 and thence into the centrifugal pump 8. The well pump 8 may be of any suitable construction for keeping the water under pressure so that no expansion or freeing of steam can take place near or at the surface of the ground. A heavy 80 duty centrifugal pump such as a Layne multi-stage centrifugal pump can be used.

This pump should be located at a sufficient distance below the surface of the ground to receive the water before its pressure has been reduced sufficiently to permit vaporization and cooling thereby. The pump may be located for example from 60 to 100 feet below the surface of the ground, or it may be located at even a lower level if 85 desired.

The water pumped from the ground passes through the pipe 13 to the well 1 where it is again forced down into the ground. A pump 17 is provided which may 105 supplement the centrifugal pump 8, but with a suitable centrifugal pump, the pump 17 may be omitted, or may be used only for supplementing the centrifugal pump as occasion may arise for doing so.

By withdrawing the hot water from the mine in this way and maintaining it under pressure and at its original temperature, or with only a minimum drop in temperature, the water can be used over again in a different location of the mine for melting further amounts of sulphur. This re-utilization of the hot mine water results in large economies as compared with ordinary mining operation where hot water is provided and pumped down into the mine for melting the sulphur and where the heat required for heating the fresh water, e. g. from 68° to around 324° F. is 256 B. t. u.'s. By avoiding the necessity of supplying such fresh hot water, and by utilizing the accumulated hot water from the mine, it becomes possible to avoid the large consumption of heat now involved in commercial mining operation.

At the beginning of the mining operations of the dome, the sulphur wells are advantageously located near the top of the dome near the location of the well 6 and such wells 5 are operated until the sulphur is exhausted at that location or until subsidence of the ground causes breaking of the piping equipment. As the ground surrounding the first wells becomes exhausted, additional 10 wells are drilled at a distance from the first wells. These wells may be at a location such as illustrated by the well 1 in the drawing and the well 6 may be an exhausted well which is used merely for the purpose 15 of withdrawing the hot water from the upper part of the deposit. The upper part of the deposit forms a heat reservoir where the hottest water tends to accumulate in a portion of the deposit from which the 20 sulphur has been exhausted and in the porous caprock where it serves no useful purpose in melting sulphur and where it causes great heat loss and low heat efficiency.

Such operations represent the usual operations and it is from such operations that the present invention is differentiated. Instead of introducing additional hot water as in such prior operations, the process of the present invention is carried out with the 25 use of the hot water accumulated in the deposit itself. If this water is withdrawn through bleeder wells, the reduction in pressure will cause reduction in temperature by vaporization and the water escaping at the 30 surface will have a temperature not exceeding 212° F. which is a temperature too low for further use in the melting of sulphur. According to the present invention, such reduction in temperature due to vapor- 35 ization is avoided by maintaining the hot water under a sufficient pressure to prevent cooling by vaporization so that it can be maintained at substantially its original temperature and reintroduced into an oper- 40 ating well or wells while still under pressure and at approximately its original temperature. If, for example, the temperature of the accumulated body of hot water in the deposit is in the neighborhood of 275 to 50 300° F., this water is withdrawn under sufficient pressure to prevent vaporization and cooling and is kept under pressure and forced again down into the deposit at the operating well or wells at a temperature 55 approximately the same as that of withdrawal from the underground body of hot water or with only a small temperature drop due to heat losses other than by vaporization during the recirculation. To avoid even 60 this decrease in temperature the water may be heated to the necessary extent, e. g. by injection of steam at a sufficiently high temperature so that the water reintroduced into the deposit will be at a temperature 65 substantially the same as that of the water

withdrawn or not materially below such temperature.

In my prior application, Serial No. 699-448, I have described and claimed a process in which the water withdrawn from the deposit is further heated to increase its temperature by a mixture with additional amounts of super-heated water in regulated proportion. The present application is a continuation of said prior application, but 70 the invention claimed in the present application is limited to a process in which the hot water withdrawn from the deposit is used over again by pumping it back into the deposit without any material increase 75 in temperature, the hot water from the deposit being withdrawn at a sufficiently high temperature and being maintained at such temperature and being reintroduced while still at a sufficiently high temperature, without additional heating to any considerable extent, so that it is made use of for further mining operations.

The present process can be considered to involve a re-utilization of the hot accumulated mine water by recirculating it from the exhausted portion of the deposit to a part of the deposit where mining is to be carried on. Where this recirculation is accomplished by withdrawing the super-heated water from its zone of high pressure, the advantages of the high temperature would be lost by reduction in pressure and resulting vaporization if the pressure were not maintained; but by maintaining the pressure on the water withdrawn so that the water at the surface of the ground passing through the circulating line is under a correspondingly high pressure, the superheated character of the water is 100 maintained and this is made use of by pumping the water down in the operating well or wells where its high temperature is made use of for melting additional sulphur.

Instead of requiring a large amount of 110 fresh superheated water, with the large fuel consumption necessary to produce it, the present invention practically eliminates the need of supplying heat except for the mechanical operations of pumping, compressing air for the pumping of sulphur, lighting, heating, etc.

The present invention not only makes use 120 of the accumulated hot water which is ordinarily considered to have served its usefulness, but it applies this in a localized way at the points of the further mining operations such that there may be considered to be a cycle of circulation from the hot water at the top of the deposit through the outside circulating line where the water is maintained under pressure to the operating well or wells where the hot water serves to melt additional sulphur and thence under- 125 ground through the deposit from the operat- 130

ing well or wells to the accumulated body of hot water in the sulphur deposit. By circulating large amounts of the water in this way a similar heating effect can be obtained as where more highly superheated water is introduced into the deposit. Overheating locally may thus be avoided and a more uniform distribution of the hot water underground obtained because of the greater 10 volume of water circulated and because of the decreased difference in density or specific gravity between the water so introduced and the surrounding water of the deposit.

15 The present invention includes as an apparatus or system an arrangement of wells, one or more of which is connected with the hot accumulated body of water in the dome and one or more of which are used as 20 the active operating wells, with outside connections such that the water can be withdrawn and directly reintroduced, without substantial loss of temperature, and maintained continuously under pressure. This 25 system or apparatus requires only suitable pumping means and pipe connections for withdrawing the hot water and maintaining it under pressure and for conveying it to the operating mines and forcing it down into 30 the deposit.

Where the mining operation is carried out with a hot brine of high specific gravity, which tends to settle to the bottom of the sulphur deposit, this accumulated, heavy 35 brine can, after it has reached a sufficient volume and temperature, be withdrawn and reintroduced in a similar manner to that above described in connection with the use 40 of hot water. The operation will be somewhat reversed, however, in that the heavy brine will be introduced at a higher level than that from which it is withdrawn and the accumulated body of hot brine will be in the lower parts of the sulphur mine or 45 deposit rather than in the upper portion thereof.

I claim:

1. The improvement in the mining of sulphur by underground fusion from partially exhausted sulphur deposits, which 50 comprises withdrawing from the upper part of a deposit hot water at a temperature higher than the melting point of sulphur, maintaining the temperature of the water 55 above the melting point of sulphur, and reintroducing the withdrawn hot water into the deposit at a localized well zone remote from the point of withdrawal.

2. The improvement in the mining of sulphur by underground fusion from partially exhausted sulphur deposits, which comprises withdrawing from the upper part of the deposit hot water above the melting point of sulphur, which water has preferentially 60 accumulated in the upper part of the deposit,

maintaining the temperature of the withdrawn water above the melting point of sulphur, withdrawing cold water at a temperature below the melting point of sulphur, and reintroducing the withdrawn hot water 70 into the deposit at a localized well zone remote from the point of withdrawal.

3. The improvement in the mining of sulphur by underground fusion from partially exhausted sulphur deposits, which comprises 75 withdrawing part of the hottest water from the exhausted upper part of a deposit, maintaining the water withdrawn under pressure to prevent vaporization and lowering of temperature below the melting point of sulphur, and reintroducing the withdrawn hot water at a localized well zone remote from the point of withdrawal.

4. The improvement in the mining of sulphur by underground fusion from partially exhausted sulphur deposits, which comprises withdrawing from the deposit hot brine at a temperature considerably above the melting point of sulphur, maintaining the withdrawn brine under pressure to prevent vaporization and cooling below the melting point of sulphur, and reintroducing the withdrawn hot brine into the deposit at a well zone remote from the point of withdrawal.

5. In the mining of sulphur by underground fusion from partially exhausted sulphur deposits, one or more wells arranged to permit the withdrawal of hot water at a temperature above the melting point of sulphur from near the top of the deposit, one or more wells arranged for conducting superheated water into the sulphur containing formation, means for pumping hot water from the said withdrawing wells and maintaining it under pressure from the top of the deposit to the surface of the ground, and means for reintroducing, still under pressure, the withdrawn hot water into the sulphur mining well or wells as the heating medium 100 therefor.

6. In the mining of sulphur one or more wells extending to the sulphur containing deposit for introducing superheated water into the deposit and removing the molten sulphur therefrom, one or more wells extending to the upper part of the deposit from which the sulphur has been exhausted, pumps so located and designed to withdraw hot water at a temperature above the melting point of sulphur from the upper part of the deposit through the last mentioned wells, means for maintaining the withdrawn hot water under pressure and returning it to said first mentioned wells, and means for withdrawing cold water at a temperature below the melting point of sulphur from a lower level of the deposit.

In testimony whereof I affix my signature.
ROBERT HOLDEN STEWART.
